UNITED STATES PATENT OFFICE.

AXEL V. YOUNG, OF DE BEQUE, COLORADO.

RETORT FOR EXTRACTING OIL, &c.

1,378,643.

Specification of Letters Patent. Patented May 17, 1921.

Application filed February 20, 1919. Serial No. 278,128.

To all whom it may concern:

Be it known that I, AXEL V. YOUNG, a citizen of the United States, and a resident of De Beque, in the county of Mesa and State of Colorado, have invented a new and Improved Retort for Extracting Oil, &c., of which the following is a full, clear, and exact description.

The present invention relates to the extraction of oil, gas, and other products from shale, oil sand, coal, etc., by destructive distillation; and has for an object to provide an improved kiln and to provide an improved process for the extraction of oil, gas, etc., from ores and the like. The invention provides an improved process, which consists in heating the material to a sufficient temperature to drive off the gas, oil or the like and condense the gaseous products driven off.

In the drawings is shown an improved kiln which conveniently may be used to accomplish the improved process and which, furthermore, is capable of other uses, the use of the kiln not being limited to the accomplishment of the process herein described.

In the drawings,—

Figure 1 is a longitudinal sectional view of the kiln or retort;

Fig. 2 is a transverse sectional view taken on the line 2—2, Fig. 1; and

Fig. 3 is a detailed perspective view of the conveyer chain.

In the drawings, the kiln shown provides a substantially closed retort 1 into which the material may conveniently be fed from a hopper 2 by means of a feeder wheel 3, the feeder wheel being driven at a speed to provide the necessary feed. Within the retort 4 a conveyer chain 4, passing over sprocket wheels 5 and 6 and driven thereby, provides means for pushing the material along the bottom 26 of the retort. The material in the hopper provides a sufficient gas check 45 to prevent the escape of the products of distillation. A discharge outlet 7 permits the discharge of the spent material.

The retort is provided with a manifold 9 to provide an outlet for the gases and vapors, and the same may be passed therefrom to any suitable condenser to separate the condensable products from the fixed gases in a manner well known in the art.

The conveyer chain 4 may be of any suitable type. That illustrated in Fig. 3 provides staggered, downwardly-extending

pusher feet 10 and 11 which project downwardly from the center and sides of alternate links.

In order to prevent the clogging of the sprocket wheel 6 with such material as may work above the top of the conveyer chain, a clearer bar 12 is provided extending transversely of the chain and closely thereabove. This clearer bar is positioned at an angle to cause the material to be forced downwardly through the chain.

A door 13 provides convenient access to the interior of the retort. The bottom of the retort slopes downwardly from back to front to facilitate the travel of the material. In the construction shown, and preferably, the bottom of the retort is arched longitudinally from front to back as shown at 26, in order that a better contact between the conveyer chain and the bottom of the retort may be provided to facilitate the feeding of the material by the pusher feet of the chain.

By having the bottom of the retort arched longitudinally, it may be made of a separate piece, in addition to the fact that it holds the bottom lap or portion of the endless feed member or chain upwardly disposed, thereby keeping the upper lap or portion 85 taut and preventing vertical or upward and downward movement or riding of the lower lap of the feeder or chain. In addition, it strengthens the bottom portion and obviates the necessity of forming the body of the retort in one piece so as to render the same extremely heavy, expensive and cumbersome, as where said bottom portion is arched transversely or horizontally, or made concaved or dished out, as is the case with ordinary retorts.

Beneath the bottom of the retort is provided a fire box 14 and combustion chamber 15, the fire box being beneath the lower end of the retort, providing thereby the greatest heat at the lower end, whereby the material is subjected to a gradually increasing heat as it passes through the retort beneath the bottom portion 26. An outlet flue 16 leads the products of combustion from the combustion chamber.

The retort bottom is constructed from flanged sections 18, which may be of iron, fire clay, or other suitable material. The adjacent flanges 19 are riveted together to provide a tight joint. The outer flanges 20 are secured to the side walls, longitudinal

angle bars or irons secured to said side walls, being preferably used for this purpose.

A seal is preferably provided at the discharge outlet to prevent the intake of air. 5 Such seal is conventionally illustrated as a flap valve 22 which is normally held upwardly in a closed position, but permitting the material to discharge or drop through the outlet 7.

10 Having thus described my invention, I claim as new and desire to secure by Letters Patent:

1. A retort of the character described, comprising a retort proper having an inclined bottom arched upwardly longitudinally thereof, a hopper, means to feed material from said hopper to the retort, sprocket wheels at opposite ends of the retort adjacent the bottom thereof, a conveyer 20 chain mounted on said sprocket wheels to be driven thereby, said chain having depending pusher feet operative to push the material downwardly along said inclined bottom, and means to heat said retort.

25 2. A retort of the class described, comprising a retort having an inclined bottom wall arched upwardly longitudinally thereof, a hopper, means to feed material from said hopper to the retort uniformly, an endless 30 member having bearing at the ends of the hopper and provided with staggered pusher feet operative to push the material downwardly along said inclined bottom, means to heat the retort at the bottom, and means 35 to discharge the material as treated.

3. A retort of the character described,

comprising a closed retort shell having a plurality of outlets for the gases and vapors at the top thereof, a bottom for said shell and arched longitudinally so that the intermediate portion is highest, shafts mounted transversely of the ends of the shell, an endless feeder member mounted to operate with said shafts and having the lower lap thereof 40 hugging the bottom of the shell, and means to supply heat beneath said bottom portion at the lowest part thereof, whereby the material fed along the same will be subjected to a gradually decreasing temperature toward the upper end. 45

4. A retort of the character described, comprising a closed retort shell having a plurality of outlets for the gases and vapors at the top thereof, a bottom for said shell and arched longitudinally but rectilinear 55 transversely so that the intermediate portion is highest, shafts mounted transversely of the ends of the shell, an endless feeder member mounted to operate with said shafts and having the lower lap thereof hugging 60 the bottom of the shell, means for feeding the material at the top of the shell to the upper end of the endless member, means for removing the material from between the laps of the endless member at the lower 65 end, a discharge member at the lower end of the shell, means for normally closing said discharge opening, means for supplying heat beneath said bottom portion, and an outlet for products of combustion from said 70 heating means.

AXEL V. YOUNG.
